NEVADA

METHOD OF AND MEANS FOR APPLYING PLASTER LATH TO STUDDING

Application filed September 10, 1927. Serial No. 218,813.

This invention relates to improvements in the building art and particularly to walls of that type set forth and to be erected in accordance with the general plans set forth in 5 the Makowski Patent No. 1,579,377. According to the teachings of said patent the wall is made up of supporting studs and then lathing strips are laid promiscuously across the face of the studs and fastened to the studs and to 10 each other in whatever position they may chance to be laid relative to the studs. The lathing strips are then plastered over or otherwise treated as may be desired to finish the wall.

15 The present invention is directed particularly to a specific method and means for fastening the plaster lath when laid against the studs in accordance with the theories of said above named patent, in a rapid and effective 20 manner, and with the operator being compelled to work only from the front of the wall.

A further object of the invention is to produce a very simple and effective fastening 25 means whereby the lath may be very securely and very tightly attached to the studding without a great deal of expense for either labor or material.

These objects we accomplish by means of 30 such structure and relative arrangement of parts as will fully appear by a perusal of the following specification and claim.

In the drawings similar characters of reference indicate corresponding parts in the 35 several views:

Fig. 1 is a perspective view of a fragmentary portion of a number of courses of the wall secured to the vertical studs in accordance with our present invention.

40 Fig. 2 is a sectional view through the stud and a portion of the plaster lath showing a fastening clip in the position it would assume just prior to its being pinched into fastening position by the pinching tool, a fragmentary outline of which is shown in the view.

45 Fig. 3 is a similar view showing the fastening element after it has been pinched to fastening position.

Fig. 4 is a perspective view of the fastening element.

Referring now more particularly to the characters of reference on the drawings, the numeral 1 designates the upright metal studs which are of the usual channel shape, and the legs 1a of which are preferably provided with the inside beveled surfaces as at 1b.

The numeral 2 designates the plaster board lath which for the purpose of the application of the present invention, is made in strips approximately six feet long and from 50 twelve to eighteen inches wide. The ordinances of most cities require that the lath be secured to the studding at various points, usually about six inches apart, and to that end in carrying out our present invention 55 the lath is provided with a series of longitudinal slots cut through the lath at the fastening points, and being of a sufficient length to allow the lath to be shifted one way or the other to fastening position in accordance 60 with the practices taught by the above identified patent. When thus positioned the slots 65 3 will usually lie immediately adjacent and from side to side of a stud and will then be 70 fixed tightly against the stud by means of 75 the use of the following method and instrumentalities, to-wit:

We provide a fastening element comprising 80 in a clip or like element having a flat front face 4 and intermediate prongs 5 and 6 projecting at right angles to the face 4. The prong 6 has a detent 7 projecting at substantially 85 right angles thereto, the inner face of same as at 8 being beveled to substantially conform to the bevel 1b of the leg 1a of the channel 1 when the detent is moved into 90 frictional engagement therewith. The distance between the body and the beveled surface of the prong is slightly less than the combined widths of the lath and beveled leg 95 of the stud so that the wedging action hereafter described may be had.

The fastening element is preferably positioned by means of the following operation:

It is first placed within the co-acting jaws 95 of the pinching tool 9, which may be of any desired type. The tool carrying the fastening element is then projected through the slot 3. The distance between the prong 5 and the end of the detent 7 is sufficiently wide to 100

allow the same to straddle the stud 1, as clearly shown in Fig. 2. When the fastening element has been positioned so that the flat surface 4 is against the face of the lath the tool 9 is operated to pinch the prongs 5 and 6 towards each other. This causes the beveled surface 8 of the detent 7 to ride the beveled surface 1b of the leg 1a and brings the prong 5 into direct frictional contact with the flat side of the stud 1. The frictional engaging surfaces 8 and 1b have a wedging effect to draw the flat plate 4 into close frictional engagement with the front face of the lath and to force same into tight contact against the stud, and the engagement of the detent 7 with the leg of the stud and of the prong 5 against the flat of the stud holds the fastening element securely in position, as will be apparent.

Thus the lath may be fastened at a plurality of the points along the stud and the free meeting ends of the lath off the stud are fastened to each other and to the edges of the adjacent laths by the clips 10 in the manner and form shown in the patent mentioned in the preamble to this specification.

It will be apparent from this description that by means of our improved method and instrumentalities plaster board lath may be quickly mounted against the metal stud and there securely fastened at a number of points in a most admirable way and with a minimum expense of time, labor and material, all of which is quite essential to an efficient and economical erection of walls of this type in class A buildings.

Having thus described our invention what we claim as new and useful and desire to secure by Letters Patent is:

A fastening element for use in securing plaster lath to a channel stud, the inner face of the leg of which is beveled, comprising a body and projecting prongs, one prong having a detent at one end thereof, the inner surface of the detent being beveled and the distance from the body to the beveled surface being less than the combined width of the lath and stud leg which are to be joined together, the two prongs lying normally in the same plane and the detent prong being bent in that plane out of its stud engaging position.

In testimony whereof we affix our signatures.

WILLIAM B. THURMAN.
MARK W. HILD.
